UNITED STATES PATENT OFFICE.

FERDINAND EPHRAIM, OF SAN FRANCISCO, CALIFORNIA.

BOOT OR SHOE.

SPECIFICATION forming part of Letters Patent No. 591,646, dated October 12, 1897.

Application filed February 11, 1897. Serial No. 622,926. (No model.)

To all whom it may concern:

Be it known that I, FERDINAND EPHRAIM, a citizen of the United States, residing at San Francisco, in the county of San Francisco and State of California, have invented certain new and useful Improvements in Boots or Shoes; and I do hereby declare that the following is a full, clear, and exact description thereof.

The present invention relates to a certain new and useful protecting-plate for boots and shoes, which is designed for use more especially in connection with rubber boots or shoes; and it consists in the arrangement of parts and details of construction, as will be hereinafter fully set forth in the drawings, and described and pointed out in the specification.

The difficulty experienced in protecting the soles of rubber boots and shoes by nails or by the ordinary plate secured thereon is that the holes or punctures formed by the nails or screws penetrating into the rubber causes the boots or shoes to leak, besides the tendency which the nails or plates have, owing to the elasticity of the rubber, to pull out or tear away from the sole.

The object of my invention is to provide a protecting-plate so constructed as to permit of being secured to the sole of the boot or shoe without the employment of nails, screws, or other devices which penetrate into the sole of the boot or shoe.

Referring to the drawings forming a part of the application, Figure 1 is a side view, in elevation, of a boot with the protecting-plates secured thereto. Fig. 2 is a broken cross-sectional view, taken on line $\alpha\alpha$, Fig. 1; and Fig. 3 is a detail view, showing a modification of the protecting-plate.

In the drawings the letter A is used to indicate the inner sole of the boot or shoe and A' is used to indicate the outer sole attached thereto. Over this sole is fitted a series of protecting-plates B, which are formed like unto a loop, the upper surface of which is interposed between the soles A A', while the

under surface is exposed across or transverse the under face of the sole A'. To an ordinary boot or shoe sole I secure four or more protecting-plates, which may vary from half an inch to one-inch in width. These plates are made of thin metal or other material possessing stronger wearing qualities than the sole itself. The size of the plates, it will be understood, varies in accordance with the various size soles.

In practice the plates or bands are slipped onto and adjusted upon the outer sole A' before the said sole is secured to the inner or upper sole A, after which the outer sole is secured to the upper or inner sole in the usual manner.

By preference the protecting plate or band is formed from a single piece of material having the ends united; but this is immaterial, as it may consist of the piece B', having the ends a flanged over or turned inward, so as to fit between the two soles of the boot or shoe.

I am aware that it is old to protect the sole of boots and shoes with metallic plates or straps united thereto by lugs, screws, &c., as fully set forth and described in United States Letters Patent Nos. 397,250 and 354,728, and I do not claim or wish to be understood as claiming such idea broadly.

Having thus described my invention, what I claim as new, and desire to secure protection in by Letters Patent, is--

In a boot or shoe, the combination with the inner and outer sole thereof, of a protecting-plate consisting of a single piece of metal arranged between the said soles and having its lower body portion run transverse of the under face of the outer sole.

In testimony whereof I affix my signature, in presence of two witnesses, this 1st day of February, 1897.

FERDINAND EPHRAIM.

Witnesses:
